MOUNT DIPPING MACHINE

Elmer E. Dotterer and Wilbert E. Van Gorder, Mill Hall, Pa., assignors, by mesne assignments, to Sylvania Electric Products Inc., Wilmington, Del., a corporation of Delaware

Filed Dec. 9, 1957, Ser. No. 701,448

7 Claims. (Cl. 134—159)

This invention relates to article handling. It relates to a means for multiple clamping of a number of equi-sized objects between sets of fixed and movable clamping elements. More specifically it relates to the handling of articles whereby they may all be temporarily loaded in a tray and inverted while in the tray for some treatment, as, immersed within a cleaning fluid.

In the manufacture of electron tubes, it has been found necessary to wash electrode elements after they have been assembled with respect to each other and fixed on to a supporting stem with exhaust tabulation affixed thereto, the stem forming the base of the finished tube. This assembly or mount with tubulated stem is subsequently sealed into a bulb and after further treatment becomes the finished tube. In the past these mounts with their tubulated stems were washed by being first placed in trays with multiple rows of aligned holes in the upper surface, the lower ends of the exhaust tubes of the stems being received within the holes. These trays were then placed in a loading rack with guide holes at opposite ends of the rack. Then rectangular bars were individually or in pairs threaded through the holes, one bar for each row of mounts, the bars overlying the stems to prevent their falling out when the trays and racks were inverted. This was a rather clumsy time consuming mechanism and also necessitated the multiplication of racks, if more than one tray was prepared for immersion each associated with its rack, as was often the case, even though the immersions were for a few seconds.

In improved structure suitable for washing mounts is described and claimed in the application of Elmer E. Dotterer et al., Serial No. 616,812, filed October 18, 1956, assigned to the assignee of the instant application, to which reference may be made for a fuller disclosure. Therein a multiple number of pairs of clamping bars are mounted in a swinging tray holder, which bars are automatically moved relatively to each other to clamp tubulations between respective pairs of bars as the tray holder is inverted to immerse the mounts in the fluid.

An object of this invention is to simplify the mechanism which clamps the tubulations while still efficiently holding parts against falling out of the tray while the tray holder is inverted.

Another object of the invention is to provide a simple and efficient counterbalancing mechanism for the tray and tray holder such that the holder is normally held at a substantially vertical position for draining of the mounts and yet counterbalanced in each of the extreme positions of the holder.

Other objects will become apparent upon consideration of the following specification when taken in conjunction with the accompanying drawings in which:

Fig. 1 is a perspective view of the mount washing machine;

Fig. 2 is a perspective view of the tray holding frame; Fig. 3 is a view of a fragmental portion of the tray;

2

Fig. 4 is a side elevation of the machine with the frame in tray loading position;

Fig. 5 is a vertical section through one of the bars showing the bores for retaining the tubulations;

Fig. 6 is a front view showing the tray in a position wherein the tubulations are not clamped and

Fig. 7 is a perspective view showing the tray in tubulation clamping position.

Now referring to the drawing in greater detail at 10

10 there is indicated a framework having a table top 11 supporting a tank 12 adapted to contain a cleansing solution. Toward the rear of the tank is a shaft 14 mounted in bearings on the top 15 of the tank. This shaft is fixedly secured within the rearwardly extending ends

15 of two spacers 16 and 18 as by screws 20, the spacers acting in the fashion of a way or guide for a tray. Fastened to one end of the shaft is a sprocket wheel 22 linked by a sprocket chain 24 to a second sprocket wheel 26 in turn fixed to a shaft 28 on which is mounted a

20 drum, preferably a spoked sheave 30. Fastened to the frame adjacent the sheave is a plate 32 mounting a pair of guide rolls 34. A spanner 36 is secured to two of the spokes as by screws 38 and it bridges the space between the spokes. A cable 40 has one end threaded through an

25 opening in the sheave circumference and terminates at the bar, it being secured to the same by a cleat 42 or the like. The cable is adapted to extend around approximately a quarter of the circumference of the sheave and between the two rollers 34. Thence the cable passes

30 downwardly into a guard can 44 wherein the cable is fixed to a weight 46 loose within the can and acting as a counterweight for the parts rotatable with the shaft 14. The spacers 16 and 18 have fixed thereto below the

35 spacers, as seen in Fig. 2, a support plate 48 recessed at its forward end as at 50. Also on the forward end of the plate 48 are two guide strips 52 and 54, the strip 52 having a vertical guide face aligned with an inner vertical face of the spacer 18 and the strip 54 having a vertical guide face offset inwardly from an inner face of spacer 16.

40 Threaded through the spacer 16 is at least one adjustable stop 56. The slotted face of strip 54 is so displaced relative to the stop that when a tray, as tray 58, is slid along the plate 48 and between the strips 52 and 54, its motion will not be arrested by coming into engagement with the

45 stops 56. The tray itself comprises a base board 60, having a width slightly less than the spacing of the strips 52 and 54, atop which is secured a block 62 somewhat smaller in width and length than the base board. On the upper surface of the block is a number of parallel bars 64

50 each provided with equally spaced bores 66 with the flaring mouths 68 into which may be thrust slender articles 70 such as the exhaust tubulations of mounts and which are parts of electronic tubes during a stage in their manufacture. These tubulations are received loosely in the bores 66 and would normally fall out were the trays inverted from the position of Fig. 5.

55 Fastened to the upper edges of the spacers 16 and 18 is a tripartite laminated structure 71 comprising a pair of top and bottom layers 72 and 74 of rigid material and an intermediate layer of resilient material 76, such as soft rubber. The laminated structure described is slotted to provide fingers 78. However, the resilient layer 76 on one side of the fingers extends laterally beyond the top and bottom layers of the fingers. The holes in the several bars 64 are so lined up that when the tray is thrust in between the spacers 16 and 18, the articles extending up from the bars will align themselves in the free space between the fingers as illustrated in Fig. 6. The tray is slid in until the rear end comes up against any suitable

65 stop, but the front edge of the tray will overlie the recessed portion 50 of the support plate 48 so that the op-

erator's fingers may easily grasp the tray to pull the same out from the hollow frame which comprises a flat hollow member provided, saliently, with the side spacers 16 and 18 and top and bottom members 71 and 48. When the tray is slid into the frame, the block 62 on the side of the strip 54 is spaced from the stop 56. To effect clamping of the articles between the tray and the frame, the tray is shifted laterally toward the stop 56. This causes the articles, as glass tubulations 70 held by the bars, to move laterally against the rubber 76 distorting the same where it engages the tubulations. Undue pressure on the glass tubulations is inhibited by the stop 56 limiting the movement of the tray and therefore limiting penetration of the tubulations into the rubber. To effect the lateral shifting of the tray there is provided a motor means, here illustrated as a pair of air motors 80, mounted in recesses 82 cut into the laminated top plate 71 and the support plate 48. The motor cylinders may conveniently be supported by the top plate and support plate 48 by straps 84 spanning the recesses 82 and engaged at their ends to the top surface of the top plate and to the under surface of plate 48. Intermediate their ends the straps are secured to end caps 86 on the motor cylinders. Within the cylinders are pistons 88 whose piston rods 90 pass freely through the spacer 18 and have abutments 92 for engaging the tray block and thrusting the tray to the left as viewed in Fig. 7.

The motor is connected by flexible hoses 94 to a conventional type of valve housed in valve box 96, the valves being operated by means of their valve stem 98 to cause air to flow to move both of the pistons either to the right or left, as viewed in Fig. 6. On the sheave 30 there is an angle bar 100 adjustably carrying a valve stem operating stud 102 adapted to engage and depress the valve stem when the frame 71 is in the loading position of Fig. 4. At this time the counterweight 46 is lifted, the cable is wrapped partway about the sheave, the frame is in loading position and the motor abutments are withdrawn from the tray block. The counterweight is of small enough mass to permit the unloaded frame to remain in the position shown in Fig. 1. However the counterweight is heavy enough to maintain the frame in a substantially vertical draining position. At this time the cable 40 is straight up and down throughout its length. Fig. 1 shows the parts just short of this position. Because of the sheave cable and weight arrangement, the frame and loaded tray will also be gravitationally retained in their inverted positions displaced 180° from the loading position of the frame and with the mounts held by the tray immersed in the liquid in the tank. To move the tray from one position to the other, light manual forces are applied to the frame, although obviously motor means may be employed. Suitable piping 104 and valving 106 is employed to fill and empty the tank. Also a drain catching trough 108 is placed beneath the shaft 14 to catch any drainage from the washed mounts when the frame is adjacent the vertical position, and this trough is emptied by a drainage hose 110. Stops 112 are provided to limit the inverting movement of the frame, the stops engaging the top plate 72 of the frame when it is inverted. Angle irons 114 attached to the top plate on the tank are provided on the loading side of the tank to support the frame when it is in loading position, the top 15 for this purpose having projections 116 extending toward the loading side of the tank.

Having disclosed the invention and the best embodiment thereof, what is claimed is:

1. An article washing mechanism comprising a tank, a frame oscillatable on the tank and having a way for receiving a tray substantially narrower than the way and which tray is adapted to be loaded with longitudinal rows of vertically elongated spaced articles with ends projecting above the level of the tray, said rows being parallel to the way and the articles being held against substantial lateral motion, laterally spaced fingers fixed on the frame, each parallel to the way and in a plane above the way on

a level intermediate the top of the tray and the top of the exposed ends of the articles and adjacent the exposed ends of the articles, a plunger slidable in the frame and in a direction transverse to the way to engage a tray within the way, and means to move the plunger to cause the tray to move laterally in the way in order to effect clamping of the elongated articles against the fingers.

2. An article washing mechanism comprising a tank, a frame oscillatable on the tank and having a way for receiving a tray substantially narrower than the way and which tray is adapted to be loaded with longitudinal rows of vertically elongated spaced articles with ends projecting above the level of the tray, said rows being parallel to the way and the articles being held against substantial lateral motion, laterally spaced fingers fixed on the frame, resilient means extending laterally from the fingers each parallel to the way and in a plane above the way on a level intermediate the top of the tray and the top of the exposed ends of the articles and adjacent the exposed ends of the articles, a plunger slidable in the frame and in a direction transverse to the way to engage a tray within the way, and means to move the plunger to cause the tray to move laterally in the way in order to effect clamping of the elongated articles against the resilient means on the fingers.

3. An article washing mechanism comprising a tank, a frame oscillatable on the tank and having a way for receiving a tray substantially narrower than the way and which tray is adapted to be loaded with rows of vertically elongated articles held in the tray against substantial lateral motion, spaced fingers fixed on the frame, each parallel to the way and in a plane above the way, a plunger slidable in the frame and in a direction transverse to the way to engage a tray slid into the way, and means to move the plunger to cause an inserted tray to move laterally in the way in order to effect clamping of the elongated articles between the tray and the fingers.

4. An article washing mechanism comprising a tank, a frame oscillatable on the tank and having a way, a removable tray within and substantially narrower than the way and adapted to be loaded with rows of vertically elongated articles held in the tray against substantial lateral motion, spaced fingers fixed on the frame, each parallel to the way and in a plane above the way, a plunger slidable in the frame and in a direction transverse to the way to engage a tray slide into the way, and means to move the plunger to cause an inserted tray to move laterally in the way in order to effect clamping of the elongated articles between the tray and the fingers.

5. An article washing mechanism comprising a tank, a frame oscillatable on the tank and having a way, a removable tray within and substantially narrower than the way and adapted to be loaded with rows of vertically elongated articles held in the tray against substantial lateral motion, spaced fingers fixed on the frame, each parallel to the way and in a plane above the way, a plunger slidable in the frame and in a direction transverse to the way to engage a tray slid into the way, means to move the plunger to cause an inserted tray to move laterally in the way in order to effect clamping of the elongated articles between the tray and the fingers, and an adjustable stop threaded into the frame in position to limit the lateral movement of the tray.

6. A tank, a shaft rotatably mounted on said tank, a frame extending laterally from said shaft and fastened thereto for oscillating the shaft on oscillation of the frame, a drum in drive relationship with said shaft, a pair of guide rolls in side by side relationship and positioned below the drum and with axes in planes close to the axis of the drum, a counterweight and a cable having its upper end passing over a quadrant of the drum when the frame is in horizontal position, said cable being fastened to the drum, passing between the guide rolls and having its lower end fastened to the counterweight.

7. A tank, a shaft rotatably supported at one end of

the tank, a flat hollow frame extending horizontally laterally from the shaft and away from the tank in a position to facilitate the loose reception of a tray which tray is adapted to be loaded with laterally extending rows of elongated articles held loosely therein and having exposed ends projecting above the level of the hollow frame, said hollow frame having laterally extending fingers adapted to be positioned adjacent the projecting ends of the rows of articles, means on the frame operative to shift the tray in a direction to cause the articles to engage the fingers to be clamped against movement relative to the tray, said tray being invertible while the articles are so clamped to bring the projecting ends of said articles into the tank and means for counterbalancing said frame, said counterbalancing means comprising a drum in driven relationship with said shaft, a pair of guide rolls in side by side relationship and positioned below the drum and with axes in planes close to the axis of the drum, a coun-

terweight and a cable having its upper end fastened to the drum, and adapted to lie on the arcuate surface thereof, passing between the guide rolls and having its lower end fastened to the counterweight.
